UNITED STATES PATENT OFFICE.

JAMES NATHAN GOTENDORF, JR., OF PARIS, FRANCE, ASSIGNOR TO BRENT GOOD, OF NEW YORK, N. Y.

BUTTON-MACHINE.

SPECIFICATION forming part of Letters Patent No. 396,081, dated January 15, 1889.

Application filed March 29, 1888. Serial No. 268,752. (No model.) Patented in France December 10, 1886, No. 180,212, and in Belgium July 8, 1887, No. 78,153.

To all whom it may concern:

Be it known that I, JAMES NATHAN GOTENDORF, Jr., a citizen of the United States of America, and at present residing at Paris, in the Republic of France, have invented certain new and useful Improvements in Apparatus for the Manufacture of Covered Buttons, (for which Letters Patent have been granted in France, No. 180,212, dated December 10, 1886, and in Belgium, No. 78,153, dated July 8, 1887,) of which the following is a specification.

This invention relates to improvements in apparatus for use in the manufacture of covered buttons.

The object of the invention is to provide a tool which will serve both for gathering inward the covering fabric and for clinching the metallic parts, whereby the fabric is secured upon the shell of the button, and also for cutting out the covering fabric.

Reference is to be had to the accompanying drawings, forming part of this specification, in which like parts are indicated by like letters of reference in the several views, and in which—

Figure 1 is an elevation of the machine for covering the buttons in the position after the parts of the button have been pushed down in the mold and before being clinched. Fig. 2 is an elevation (partly in section) of the machine, the parts being shown in the position they occupy after the button is clinched. Fig. 3 is a plan, the upper part being removed. Fig. 4 shows a section of the combined punches and ring-cutter separately and in position for using the cutter. Fig. 5 is a cross-section (drawn on an enlarged scale) of the shell of a button before being covered. Fig. 6 is a similar view of the entire button after the parts are clinched together. Fig. 7 is an elevation of the collet.

The metallic shell of the button is composed of a disk, *a*, and a back, *b*, united as shown, the back having formed in one with it a neck, *c*, in which is secured the shank *d*, formed of a disk of cloth, held in place by its edges being nipped between *a* and *b* and by a cupped metal disk, *e*, having serrated edges, which

penetrate the shank *d* and enter a corresponding shoulder, *b'*, in the back *b*.

f is the covering fabric, stamped out in the form of a disk, secured at the back of the shell by a collet, *g*. This collet *g* is a cupped annular disk having a central aperture adapted to pass over the neck *c*, and having a toothed circumference, the points of the teeth *g'* being slightly convergent or directed toward the center, so that when pressed against the inwardly-turned portions of the covering fabric *f* at the back *b* of the shell, as hereinafter described, they will pierce the fabric and enter the shoulder *b'*, formed in the back *b*, and thus firmly retain the covering fabric. At the same time that the teeth *g'* are bent inward the end of the neck *c* is splayed outward and clinched over the back of the collet *g*, so as to hold the collet securely in position.

The button thus constructed forms the subject of another application for Letters Patent of the United States of even date herewith, Serial No. 268,753.

The combined tool whereby the covering fabric *f* is gathered inward and the collet *g* and neck *c* are simultaneously clinched comprises a double punch, *i* *k*, and a circular gathering hollow tool, *l*, for turning inward the edges of the covering fabric in advance of the clinching action of the punches. These parts are mounted on a sliding plunger, *m*, guided vertically in a bracket arm or frame, the plunger being raised by a spring, *m'*, and depressed by a cam, *n*, pivoted at *n'* in the head of the bracket and operated by a lever, *n'*, the cam bearing directly on the head of the plunger *m*. The central punch, *i*, whereby the neck *c* of the shell is riveted over the collet *g*, is preferably carried by an inner stem, *i'*, sliding through the main plunger *m*, which is tubular, and is slotted at the upper part to admit a small hand-lever, *i''*, pivoted at *i'''* on the bracket-arm, whereby the punch *i* may be brought down independently of the punch *k*, for the purpose of pushing the parts of the button down into proper position in the cavity of the bed-plate before the pressure is applied for clinching them together, the punch *i* being normally held up in the plunger *m* by

a spring, i^6 . The punches i k act, however, together as one, the punch i having a shoulder, i^4 , whereby when plunger m is depressed by the lever-cam n the punch i will be brought down also, and the two punches will act currently.

The punch k is screwed on the lower end of the plunger m , so as to be readily removable and reversible thereon, as hereinafter described, and upon this punch k is fitted to slide the hollow gathering-tool l , by which the edges of the covering fabric f (which, when pushed down along with the shell in the cavity of the bed-die, stand up against the sides of the cavity) are forced inward toward the center over the rear side of the back b . The punch k and the gathering-tool l have inwardly-beveled acting faces, so as to force the teeth of the collet and the edges of the covering fabric in the desired direction, while the acting face of the punch i is beveled in the opposite direction and hollowed, so as to clinch the neck c over the back of the collet. The hollow gathering-tool l is free to slide on the punch k , to which it is attached by stud-and-slot connections l' l'' , and it is carried down in advance of the punch k by a spring, l^3 , confined between the end of the tool l and a flange, k^3 , on the end of the punch, this spring yielding on the gathering-tool meeting the button in the die and permitting the punch k to come down and do its work on the collet. In one with the tool l is formed an oppositely-directed ring-cutter, h , for cutting out the covering fabric. This is brought into use when required by reversing the punch k and gathering-tool l on the plunger m . In this position (shown separately in Fig. 4) the acting face of the gathering-tool l abuts against the beveled edge of the abutment-shoulder m^2 on the plunger m , so that the pressure is transmitted directly from the latter to the cutter, and the studs l' are not strained. By screwing the nut formed in the punch k tightly upon the plunger m the punch will be raised within the cutter h until the punch also bears against the shoulder m^2 , whereby sufficient room will be provided within the cutter h for cutting out thick fabrics or several thicknesses of fabric at once.

The bed-die is formed in a circular plate, p , which has a number of cavities, r , in it of different sizes, as required for buttons of different dimensions, the plate being mounted to rotate about a central pillar, s , immediately over the base-plate t . Any one of these cavities r may be brought in line beneath the punch-plunger m , upon which a combined tool (such as shown in Figs. 1 and 2) of corresponding diameter to the cavity is secured. In the base-plate t is fitted a spring-follower, u , the head of which rises in the cavity of the bed-die to a sufficient height to form a support for the covering fabric and shell when they are first placed in the cavity and keep them horizontal while being forced down in

the cavity of the bed-plate previous to the clinching pressure being applied. The upward motion of the follower is limited by a stop, and on being depressed it is prevented from again rising by a latch, v , actuated by a spring, v' , engaging in a notch, v^2 , in the stem of the follower. In this lowered position the head of the follower is recessed in the base-plate t . 75

The disk f of covering fabric having been placed over the cavity and the metal shell having been placed face downward upon it, and the two having been pushed down to the bottom of the cavity by depressing the punch i by means of lever i^2 , (or by hand if the punch i is not independently movable,) the collet g is placed teeth downward within the parallel part of the gathering-tool l , which it fits, so as to be retained therein, and the punches i k and gathering-tool l are then brought down together by means of the cam n and lever n^2 , whereby the gathering-tool l , which is in advance of the punches, first turns the edges of the covering fabric inward, and 85 then the punch k forces the teeth of the collet through said fabric and clinches them, while the punch i clinches the neck of the shell over the collet, as above described. The finished button may then be ejected downward by first turning the plate p partly round on its center, so as to uncover the bottom of the cavity. Upon returning the plate to position the catch v is released by hand and the follower allowed to rise in readiness for making another button. 90 95 100

Besides the cavities in the plate p there are beds w , of lead or ebonite, for the cutters h to cut out the covering fabric upon, either of which may be brought into position when the cutter h is used. The plate p is held in proper position for use by a spring latch-bolt, x , engaging in its periphery. 105

It is to be understood that the disk a of the shell may be either flat or convex, according as a flat or convex face button is to be formed, the spring-follower u being made concave accordingly; or, instead of using the follower, the cavity may be simply closed at bottom by the base-plate t , or by a removable slide fitted 115 in the base-plate and having a concaved or other surface corresponding in form to the face of the button. 110

Having now particularly described and ascertained the nature of the said invention 120 and in what manner the same is to be performed, I declare that what I claim is—

1. In an apparatus for the manufacture of covered buttons, the combination, with a sliding plunger provided at its lower end with a punch, as i , whose acting face is outwardly beveled and hollowed, of a second independent punch, as k , secured to said sliding plunger in concentric relation to the first-mentioned punch, and having an inwardly-beveled acting face, whereby simultaneously with the clinching of the neck of the button 125 130 135

- the teeth of its collet may be forced inward and into the covering fabric, substantially as set forth.
2. In an apparatus for the manufacture of covered buttons, the combination, with a tubular sliding plunger provided with an inner stem, as i' , arranged to slide independently of said plunger, and carrying at its lower end a punch, as i , of a second punch, as k , secured to the lower end of said sliding plunger in concentric relation to the first-mentioned punch, whereby the punch i may be brought down independently and in advance of punch k , for pushing the parts of the button into proper position for being acted upon, and simultaneously with the clinching of the neck of the button the teeth of its collet may be forced inward and into the covering fabric, substantially as set forth.
3. In an apparatus for the manufacture of covered buttons, the combination, with a sliding plunger provided at its lower end with a punch, as i , whose acting face is beveled and hollowed, as shown, of a second independent punch, as k , secured to said sliding plunger in concentric relation to the first-mentioned punch, and having an inwardly-beveled face and a gathering-tool, as l , adapted to receive the collet of the button, and having an inwardly-beveled acting face and fitted to slide on punch k , and a spring, as v^2 , the parts being arranged whereby, first, the edges of the covering fabric are turned inwardly; second, the teeth of the collet are forced into said fabric, and, third, the neck of the shell of the button is clinched over the collet, all in one operation without change or readjustment of the operating-tools, substantially as set forth.
4. In an apparatus for the manufacture of covered buttons, the combination, with the sliding plunger, of punch k and a combined gathering-tool and ring-cutter, the latter reversible on the punch k , substantially as set forth.
5. The sliding plunger m , screw-threaded at 45 its lower end and provided with abutment m^2 , in combination with punch k , formed with an interior nut, and the combined gathering-tool and ring-cutter $l\ h$, substantially as set forth.
6. In an apparatus for covering the buttons 50 herein described, the rotary die and cutter bed-plate, in combination with the cam and spring-actuated rectilinearly-movable punching, gathering, and cutting tools, substantially as specified.
7. In an apparatus for covering buttons, 55 the combination, with the rotary die-plate, of a base-plate fitted with a spring-follower and a latch for securing said spring-follower depressed, substantially as set forth.
8. In an apparatus for covering buttons, the combination, with the rotary die-plate provided with a series of cavities, as r , of a base-plate fitted with a spring-follower having a head co-operating with said cavities, and 65 a stem provided with a notch, as v^2 , and a spring-actuated latch, v , co-operating with the notch in the follower-stem, substantially as and for the purpose set forth.
9. In an apparatus for covering buttons, a 70 recessed base-plate, t , fitted with a headed spring-follower, a spring-actuated latch, as v , a rotary die-plate provided with a series of cavities, as r , and mounted to rotate about a central pillar, s , immediately over said base- 75 plate, combined and co-operating with a punch-plunger, substantially as and for the purpose set forth.

The foregoing specification of my improvements in apparatus for the manufacture of 80 covered buttons signed by me this 27th day of February, 1888, at Paris, France.
